SELF-PRIMING IMPELLER PUMP FOR GAS AND FLUID MIXTURES

Albert C. Stratton, Lincoln Park, N. J., assignor
to Alfred S. Marlow, Ridgewood, N. J.

Application May 18, 1931, Serial No. 538,129

14 Claims. (Cl. 103—113)

This invention relates to impeller pumps for gas and fluid mixtures and more particularly to pumps of this kind which are self-priming.

In accordance with known arrangements for adapting a pump of this type for self-priming a reservoir for priming water is placed above the pump; a connection is made for supplying the reservoir from the discharge side of the pump and another connection serves to discharge the 10 reserve water to the suction side of the pump; automatic means are provided for controlling the flow of reserve water; means are also provided for separating air from the reserve water at the discharge side of the pump and means are 15 provided for mixing of reserve water and air at the suction side of the pump during priming operation.

An object of this invention is to provide a self-priming pumping arrangement of the kind just 20 described, which under ordinary operating conditions will handle gas and fluid mixtures of widely varying gas content with high efficiency and without continued loss of prime, thus eliminating the most common cause of trouble, which 25 may be ascribed to accumulation of air in the suction lines.

Another object is to enable such a pumping arrangement to quickly resume normal pumping operation when, after a failure thereof, the main 30 water supply has been replenished.

A principal object is the ability of the pumping system to develop a high degree of suction or 35 vacuum in the suction system.

Among other objects of the invention are 40 the following features of the invention may be incorporated in a pumping arrangement such as that referred to above.

The invention in its preferred form is applied 45 to a centrifugal pump of any conventional form.

The reservoir, or tank, for priming water is placed above the pump and connected directly to its discharge opening; the discharge or overflow connection from the system is connected 50 at the top of the tank. Screens, baffle plates or other means for aiding the separation of air and solids from the priming water may be located within the tank. From the lower portion of the tank a short priming connection of large cross- 55 sectional area is made to the suction opening of

the pump. The suction system is connected to this priming connection and includes a trap valve.

The control means preferably comprises a short restricted passage in the priming connection dimensioned according to requirements and located above the level of the pump axis. A movable member is arranged to automatically open and close the restricted passage under the influence of the main flow in the suction system, 5 and may also serve to deflect or disperse the stream of priming water emanating from the restricted passage. Loss of priming water may be prevented by means such as a trap valve referred to above or by a pocket formation in the 10 suction system.

These and other features in different modifications, and their coordinate functions, will be better understood, from the following description of the construction and operation of certain 15 preferred embodiments of the invention illustrated in the attached drawings.

Referring to the drawings:

Figs. 1a, b, and c show a self-priming pumping system in accordance with one embodiment of the invention; Fig. 1a being a side view partly in section showing the system under normal pumping operations; Fig. 1b being a detailed view corresponding to a portion of Fig. 1a showing the relation of certain parts under priming 20 conditions; and Fig. 1c being an end view partly in section taken on line 1c—1c of Fig. 1a;

Figs. 2a and b show a modification of the 25 automatic control arrangement shown in Fig. 1a; Fig. 2a showing the parts under normal pumping operation; and Fig. 2b showing these 30 parts under priming conditions;

Fig. 3 shows another modification of the control arrangement shown in Fig. 1a;

Figs. 4a and b show another embodiment of 40 the invention in which all free-moving mechanical parts have been eliminated from the priming system; these figures showing the parts under normal and priming conditions, respectively;

Figs. 5a and b show a modification of the 45 embodiment shown in Figs. 4a and b; Fig. 5a showing certain parts under normal operating conditions; and Fig. 5b showing these parts under priming conditions.

Referring now to the outfit illustrated in Figs. 50 1a, b and c, a centrifugal pump 20 of any conventional type has the intake side of its stationary housing extended in any convenient manner into a connector piece forming a tubular intake channel 21, which may be connected 55

through a suction pipe or hose or other convenient means 22 to the main water supply, the level of which may be as much as 28 feet below the center line A—A of the outfit. The discharge opening 23 of the pump connects to an outlet 24 through a tank 30, which is effective as a reservoir for recirculation water. The discharge circuit is completed through a direct passage such as tube 60 to an overflow or to a discharge pipe 25 or other convenient means 25 connected to outlet 24 at the top of the tank for disposal of the discharge water. The tube 60 forms a direct unrestricted passage through tank 30 and has openings or perforations for feeding reserve water to the tank. The discharge water may be spilled over at the level at which the discharge pipe 25 is shown or may connect to a head, the height of which, of course, is limited by the pressure which can be developed by the pump.

20 A recirculation path for the pump is completed from the discharge opening 23 through perforations in tube 60, tank 30, and priming connection 31 forming a wide well opening into the tank at its upper end and connecting at its lower end 25 through a short restricted passage or spout 32 to the intake channel 21 at a point immediately in front of the suction opening of the pump. A hinged member 40, located in the intake channel, carries a disc 41, which serves to open and 30 close the lower opening of the spout 32, and a vane 42, which projects into the main flow through the intake channel 21. Vane 42 is of a size such that ample space is left around its edge to permit of free passage of the intake water 35 in any position of the vane. A flap valve 50 is arranged to shut off the intake passage 21 from the suction pipe 22 for trapping the water in the main flow during priming and to prevent loss of priming water during priming or when the outfit 40 is shut down for a short time. As a further precaution the intake chamber 21 may be provided with an S connection 26 for the suction pipe to form a pocket with a water level about even with the pump axis A—A. The tube 60 45 forms a direct unrestricted passage through tank 30 to outlet 24 and is preferably placed at a small angle with the direction of the discharge flow from discharge opening 23. Openings 51, 52 and 53, which are normally closed, are provided at convenient places for cleaning of the system and refilling of tank and pump.

The pump 20 comprises the usual stationary volute or housing, which may be supported by brackets 10 of any convenient design, and a plurality of impeller blades (not shown) which rotate within the volute, being driven through shaft 71 by any convenient power supply, such as a gasoline motor. With the pump running at normal speed, the main flow of water will be pumped through pipe 22, valve 50, and past the vane 42, which due to the velocity of the water will be held in the position shown in Fig. 1a to force the disc 41 to close the spout 32; the water continues through the pump, from which it flows through opening 23 and tube 60 into the discharge pipe 25.

The perforated tubular member 60 serves to guide the main discharge flow including all solid matters of appreciable size through the discharge path just described, at the same time as it acts as a sieve or screen, allowing water to pass through its perforations and fill the tank 30, thereby maintaining a reserve supply of water for subsequent priming operations; the reserve water 75 will consequently contain only small particles

of solid matter which will not interfere with the operation of the priming equipment. Such air as may enter the tank from the tube 60 will again be able to escape through the upper perforations of the tube into the discharge pipe 25. It has 5 been found that the separation of air from the water in the tank may be aided by placing the tube 60 at an angle as shown in Fig. 1c. The main discharge flow will thus be slightly deflected and thereby cause the reserve water to rotate 10 within the tank to effect a centrifugal separation of water and air.

When the rate of flow of intake water through the intake passage 21 is reduced, the pressure on the vane 42 causes the disc 41 to fall away 15 from the spout 32 partly by gravity and partly under the pressure of the reserve water in tank 30, thereby admitting a stream of reserve water to the suction side of the pump and thus compensating at least in part for the reduction in 20 the main flow. The pump may thus continue its functioning and will be replenishing the reserve water in the tank through the screen 60.

When the main supply fails altogether the suction pipe 22 will be filled with air, the disc 41 25 will be fully open to admit the maximum volume of reserve water, which, however, in nearly all cases will be insufficient to maintain the prime in the pump. Valve 50 will be closed to prevent loss of reserve water but will admit air freely to 30 the pump. As soon as enough reserve water has collected in the pump to prime it, it will develop suction in the pipe 22 until the reserve water has been expelled from the pump, when the prime will again break. This cycle will be continually repeated until such time when the water in the main supply has risen enough to cover the foot of pipe 22. After this the drinking time begins, that is, the pump will raise the water a certain distance in the suction pipe during that 40 part of the priming cycle, just described, in which the pump is actually primed and develops a suction and the water raised will be held by the valve 50. After a number of priming cycles, the raised water enters the pump, the drinking time ends, 45 disc 41 shuts the reserve water off and normal operation is resumed.

Pumping outfits of the type to which the invention is particularly applicable, such as portable outfits for excavation work, are frequently 50 used under circumstances which make continuous and efficient operation difficult. It may, for example, be operated on suction lifts as great as 28 feet, and whereas the pump may be loaded to full capacity when the water supply is ample, 55 a leaky suction pipe may seriously reduce the load or break the prime; the water supply may at times be insufficient to continuously keep the pump fed. On well point jobs a plurality of pipes may be driven into a sand and gravel bed 60 and connected together by a main pipe leading to the suction side of the pump; even though the lift may be small, a great resistance to the flow through the sand must be overcome by a high vacuum from the pump, and much air may be 65 taken in by one or more of the points. Under such circumstances great difficulties have been experienced in the past with pumps of the centrifugal type in attempting to secure reliable self-priming operation, especially where a vacuum as 70 high as 26 to 27 inches may be required in the suction system. It is essential that a practical outfit, even at great suction depth, have a short drinking time, i. e., quickly fills the suction system and resumes normal operations to avoid dan- 75

ger of flood due to an excessive rise of the water about the suction pipe.

In a practical outfit, built in accordance with the invention, it is furthermore essential that trapping and recirculation of air be prevented; it is also necessary that the outfit be capable of being fully drained to prevent freezing during idle periods. The arrangement shown in Figs. 1a b and c is particularly adapted to meet these exigencies, as will appear from the following more detailed discussion of its functioning.

The automatic control means comprising spout 32, vane 42 and disc 41, being placed on the suction side of the pump are responsive to the main flow in the intake. This has many advantages over arrangements in which the control of the flow of reserve water into the suction side is controlled from the discharge side of the pump. Thus a single unitary device is obtained by combining the responsive and the controlling elements into a single structure requiring no mechanical connections and no piping for air or water.

The vane 42 is operated by the actual flow of water rather than by a pressure condition set up in the discharge system and is thus independent of the varying heads which the pump may be working against and operates in a more positive manner; the vane 42 being placed in the flow in the suction side rather than in the discharge side, its operation is not affected by the flow of discharge water, and since the loss of water manifests itself sooner on the suction side than on the discharge side, the time of response of the vane is advanced by this arrangement and reserve water may be supplied even before the pump loses its prime; the absence of long narrow connections between pump and tank greatly aids the quick response of reserve water to sudden changes in the position of the vane.

There are, however, other very essential features involved in the present arrangement which attach to its functioning in the presence of air in the main flow. In general, conditions in the intake passage 21 are such that air would separate from the water and pass in the upper zone of this passage; solids will tend to pass in the lower zone; the control element 42, being located in the upper zone, will not obstruct the passage of the solids or become clogged by them; the position of the vane will be directly determined by the water level in passage 21. Under steady conditions, as in case of a leak in pipe 22, the separated flow of air and water through passage 21 will be fairly uniform and the vane will admit a fairly uniform flow of reserve water, the adjustment of parts being such that the prime of the pump will be maintained. As more or less air passes, more or less reserve water will be admitted, so that the energy lost in maintaining the recirculation of reserve water is kept as low under the different conditions as is possible without the chance of the pump losing its prime. The uncertainty of pressure conditions in the discharge side due to the great variations in pump pressure, when air passes through the pump, has little effect upon the control of the reserve water, due to the relatively small orifice in spout 32 and also due to the small leverage of the action of the reserve flow on disc 41 as compared with the large leverage of the main flow acting on vane 42.

The control means is also utilized as a means for mixing air and water into a fairly uniform mixture, and its location immediately in front of the suction opening of the pump is of great impor-

tance, since the mixture is thrown into the impellers before the air has a chance to separate out, thus insuring against undue fluctuation in the operation with consequent lowering of the efficiency, but especially enabling the pump to carry 5 large quantities of air.

The mixing of air and water is partly obtained by the placing of the spout 32 in or immediately above the air zone in passage 21, since the stream of reserve water is thereby forced to pass through 10 the air zone and to contact and mix with the air. The contact is increased by deflection against disc 15 41 and consequent spraying of the reserve water into the air zone, and considerable quantities of air are thus carried along into the pump. When 20 the disc 41 moves far away from the spout 32 as in the case when the main flow is greatly reduced or fails altogether, the bar 43 in the hinged member 25 40 will be in the path of the reserve stream, which becomes partly deflected as a spray into the air 20 zone, and partly split into two streams contacting doubly with the air and being projected into the pool of water in the bottom of passage 21, thereby setting up a violent turbulence in the pool and thus forcing the air into the water; the air capacity 23 of the pump is thereby greatly increased.

The automatic control means thus correlate the function of varying the supply of reserve water to keep the pump primed and maintain high efficiency with the function of varying the capability 30 of the pump to suck air, both in accordance with variations in the main water flow.

The vacuum, which the pump will develop, will, of course, be affected by the amount of air mixed in with the water passing through the pump, but 35 aside from this the suction in the suction system is greatly affected by the flow of reserve water into the suction side of the pump; as more reserve water is admitted, as by increasing the orifice of spout 32, less water will be sucked up through pipe 40

22. Considering the conditions prevailing during a priming operation, a heavy flow of reserve water would absorb large quantities of air and thus tend to shorten the drinking time, i. e., the time for priming the system after the main supply has 45 been replenished; however, since a heavy flow of reserve water would limit the vacuum, the suction lift on which the pump can operate is limited correspondingly and consequently is determined by the orifice in spout 32. This relation is, however, of particular importance where a high vacuum is required to overcome a resistance to the suction flow as in well point jobs. As explained above, the lift in this case may be small but the flow through sand and gravel surrounding the well 50 point is greatly impeded and at times considerable quantities of air enter with the water. Thus high vacuum is essential to secure sufficient water capacity and must be coupled with a decided capability to handle air. For this purpose the 55 orifice of spout 32 must be limited to admit sufficient reserve water for mixing with air but of insufficient volume to satisfy to an appreciable extent the vacuum developed by the pump.

It has been found that for average operating 65 conditions for a portable outfit of the usual sizes, the most satisfactory operation is secured by making the area of the orifice of spout 32 approximately one sixth of the area of the discharge opening of the pump; thus for three inch, four 70 inch and six inch pumps, the spout orifices should be one and one quarter inch, one and five eighths inches and two and one half inches in diameter, respectively; however, for special conditions these dimensions may be varied considerable; thus a 75

four inch pump has been found to work in accordance with special requirements with a one and one eighth inch or a two inch orifice.

- Under any particular operating conditions the 5 most desired functioning may readily be observed and attained by varying the area of orifice 32, as by inserting bushings 33 (see Fig. 1a) of different sizes in the orifice and thereby varying the ratio of reserve flow to main suction flow.
- 10 The efficiency, as well as the successful priming operation, of a pumping system, of the present kind, depends to a large extent upon the expulsion of air from the recirculation water. To this end a straight and substantially vertical discharge 15 path through the reservoir 30 is formed by the tube 60, and the tube is provided with a large number of perforations so that the reserve water passes slowly and evenly into the tank; in this manner air bubbles may readily escape through the discharge opening 24 and they are largely 20 prevented from entering the tank. The centrifugal action in tank 60 due to the slight angle of tube 60 results in air bubbles gathering in the quiet area in the center of the tank, moving to the 25 top and escaping again through the upper perforations of tube 60. The well 31 is placed near the periphery of the tank where the rotating water contains least air and the flow through the well, being in a downward direction and very slow 30 due to the large cross-sectional area of the well, further safeguards against air in appreciable amounts passing through spout 32 with the recirculating water.

In regard to prevention of clogging by sand or 35 other solids, the arrangement just described is very effective. Like the air contained in the water, solids will tend to pass directly to the discharge pipe through tube 60, the direction and velocity of the water remaining practically unchanged in this path. The low velocity of 40 reserve water passing through the perforations into the tank will allow only fine particles to enter the tank, where they will be kept traveling along the periphery and thus be prevented from 45 lodging in the center of the tank. The particles will tend to flow down through the well, where they may readily be washed out through the spout 32 by the reserve water.

Since no connections carrying water are of 50 smaller size than the suction and discharge connections, the system has no weak points at which freezing would be especially likely to occur. No pockets exist which cannot be drained through the valve 55 at the bottom of the pump housing, 55 which also eliminates a danger of freezing.

In accordance with the modification shown in Figs. 2a and b of the system shown in Figs. 1a, b and c, the intake channel 21 comprises a ball valve chamber, containing a ball 122, having a 60 lower seat 123 for the ball opening to the suction pipe 22 and having an upper seat 124 forming part of spout 32 leading from the well 31. Suitable guides 125, of any convenient design, are arranged within the chamber for keeping the ball 65 aligned with the seats 123 and 124. The ball 122 is substantially spherical and is made of suitable material, such as an outer shell of vulcanized rubber weighted by an iron core.

Under normal pumping operations the inflow 70 of water through suction pipe 22 will hold the ball 122 pressed against the seat 124, thereby shutting off the flow of recirculating water from the well 31 connecting to tank 30. The main flow finds its way around the ball and into the suction 75 side of the pump 20.

Under priming conditions the ball settles on the lower seat 123 and permits free recirculation of water from the tank 30 to maintain the prime of the pump, at the same time as it prevents loss of recirculating water into the suction pipe 22.

Under conditions when the intake flow carries a substantial proportion of air, the ball will take an intermediate position between the two seats 123 and 124 determined by the proportion of air to water in the main flow, thereby admitting sufficient water from the tank 30 to maintain the prime.

In this modification, as in the embodiment shown in Fig. 1a, the control of recirculating water is effected by the proportion of air to water 15 in the main flow. An air zone is provided in the intake chamber around the spout 32, and the recirculating water emitted from the spout will be deflected and spread into the air zone by the surface of the ball 122, thereby securing a thorough 20 mixing of air and water at the entrance to the pump and consequently insuring a high vacuum.

The arrangement shown in Fig. 3 is a modification of the embodiment illustrated in Fig. 1a and is characterized by additional means for controlling the flow of reserve water into the intake chamber 21, which means comprises a diaphragm controlled operating device 210 affected by the back pressure in the discharge system to control the position of the hinged member 40 in conjunction with the control exerted on that member by the main flow.

This modification is particularly adapted for operation of the pump against a considerable head and the purpose of the device 210 is principally to permit an adjustment pressure to be applied to the hinged member 40 in such a way that a large back pressure acting thereon through the spout 32 may be substantially neutralized.

The device 210 comprises a diaphragm 211 mounted in a housing 212 having openings 213 for admitting the water and pressure from tank 30 to the upper side of the diaphragm. The lower part of the housing 212 is connected to a tubular member 214 which extends through the bottom portion of the well 31 into the intake chamber 21, so that the pressure, at any time existing in that chamber, may be directly communicated to the lower side of the diaphragm 211. A rod 215 is connected to the center of the diaphragm and passes through suitable guiding means 216 at the lower end of tube 214, where it terminates in a flattened portion 217. The rod 215 engages an extension 218 on the hinged member 40 at a point where the downward pressure, transmitted through the rod from the diaphragm 211, will counteract the pressure exerted from the tank on the member 40 through the spout 32. A spring 220 is mounted in the upper portion of housing 212 and may be adjusted by means of thumb screws 221 to apply a pressure to the center of the diaphragm 211 in accordance with particular requirements; depending on the circumstances, this spring pressure may be aiding or opposing the back pressure acting on the diaphragm.

The embodiment of the invention shown in Figs. 4a and b comprises a pump 20 of the centrifugal type having its discharge opening 23 connected to tank 30 and through a tubular filter 60 to the discharge system 25. The suction side 70 of the pump connects through the intake passage 321 and an intake opening 322, in the bottom of tank 30, to a tubular riser 323, placed within the tank 30 and in turn connecting through the top of the tank 30 to the suction system 22. The 75

riser 323 has an upper portion 324, which carries a flexible annular operating member 325, and a lower portion 326, the upper edge of which forms a seat for the flexible member 325. The member 325 may be of rubber or other suitable material and may be stiffened by metal. A trap valve (not shown) of any type should be included in the suction system.

The normal flow through the pump is as follows:—From the main supply through intake system 22, riser 323, intake channel 321, pump 20, tubular passage of filter 60, and discharge system 25. Under normal operating conditions, when ample water is taken in, the passing of water through the riser 323 causes the flexible member 325 to seat tightly against the portion 326, thereby shutting off the reserve flow. Under priming conditions, or when the proportion of water in the main flow is very small, the pressure on the upper side of flexible member 325 is lowered, causing the member 325 to assume its natural position, such as shown in Fig. 4b, or, dependent upon the rate of water taken in, to assume some intermediate position, thereby admitting water from the tank through the space between flexible member 325 and the seat of 326 into the intake passage 321.

In the present embodiment the reserve water, entering under the flexible member 325, is ejected into a region of the intake system which is passed by any air that may be contained in the main flow and which is located well above the center line A—A of the pump. Intimate mixing of air and water and consequent high suction is thus insured by the ejection of reserve water into the passing air, as well as by the turbulence in the pool which always lodges below the line A—A in the intake passage 321. Also by this arrangement the reserve water is controlled by the proportion of air to water in the main flow to insure a water supply to the pump which is sufficient to prevent breaking of the prime, as well as to insure high efficiency by admitting only enough recirculating water under any particular condition to provide effective operation of the pump.

The modification shown in Figs. 5a and b of the embodiment shown in Figs. 4a and b in the main differs from that embodiment in that the flexible member 425 carried by the upper portion 424 of the riser 423 has a tubular extension 427 reaching in a downward direction towards the intake channel 321 and has an upper flared portion 428, which is clamped between rings 430 and 431 to the upper portion 424 of the riser 423. The upper edge of the lower portion 426 of the riser 423 forms a seat for the flared portion of flexible member 425. The ring 431 is provided with one or more passages 432 for admission of reserve water from the tank 30 to the seat on lower portion 426. The tubular portion 427 of flexible member 425 may be stiffened by a metal tube 429 or by other suitable means.

Under normal operating conditions a heavy flow of water will cause the flexible member 425 to take a position such as shown in Fig. 5a and thereby to substantially shut off the flow of reserve water. When the flow of water is reduced or altogether fails, the flexible member will change its shape, as shown in Fig. 5b, partly due to the pressure on the outside of the tubular portion 427 by the water in tank 30 and partly due to the reduced pressure or vacuum in the riser 423.

In this figure the discharge opening 23 is shown

to lead directly into tank 30. A shield 460 surrounds the riser 423 and is provided with perforations 461 near the bottom of tank 30, thereby preventing coarse particles from entering the passages 432 and interfering with the automatic control of the reserve water. This arrangement may, of course, be replaced by the tubular screen shown in Fig. 1a, and it may replace the tubular screen in any of the other embodiments described above, depending upon the constituency of the pumping medium in any particular case. It is also within the scope of the invention to arrange other forms of baffle plates and screens for the purpose of separating air or solids from the water.

In the specification and claims the terms "water" and "liquid", "air" and "gas", "centrifugal pump" and "impeller pump" are intended to be equivalent terms, respectively, for the purposes of the invention.

What is claimed is:

1. A pumping system for pumping varying mixtures of air and water which comprises a centrifugal pump having a suction opening, a suction connection for the main water flow into said opening, a recirculation path for said pump of negligible impedance and effective as a reservoir for priming water, a short restricted passage forming the junction between said path and said suction connection and presenting substantially the total impedance to flow in said path, and a shutter member for said passage having a plurality of surfaces for impact with the reserve flow through said passage and fastened to extend into the air zone within said suction connection for operation by varying impact with the main flow through said suction connection to shut off the reserve flow through said passage.

2. A pumping system comprising a centrifugal pump, a suction connection for the main water flow, a recirculation path for said pump including a reservoir, control means for recirculation water from said reservoir, said control means comprising a restricted outlet from said path opening directly into said suction connection above the level of the center of said pump and an automatic shutter for said outlet placed within said suction connection, said automatic shutter comprising a deflecting member for scattering the stream of recirculating water directly into the air carried by the main flow.

3. A self-priming centrifugal pump comprising an impeller chamber, a suction line leading into said impeller chamber, an impeller in said chamber, a container for priming fluid associated with said chamber, a port leading from said container to said impeller chamber, a discharge passage leading from said impeller chamber, a valve for controlling said port to admit priming fluid to said impeller chamber when open and to substantially exclude priming fluid therefrom when closed, and means for holding said valve open to admit priming fluid to said impeller chamber until the air is substantially exhausted from the suction line and until a fluid flow with a selected velocity head is established therein and thereafter closing said valve and maintaining it closed while this condition continues to exist, said last named means comprising a baffle member of less area than the cross-section of the suction line projecting into the path of flow of the fluid therein but moveable substantially out of said path of flow by the action thereon of said selected velocity head of fluid.

4. A pumping system comprising a centrifugal

75

pump having discharge and suction openings, a tank for reserve water connected directly between said openings, forming substantially the total of a recirculation path for said pump, a suction connection communicating with said suction opening, automatic control means comprising a short, restricted passage, forming substantially the total impedance to the recirculation of reserve water through said path and a shutter 10 responsive to the ratio of air to water in the main suction flow to regulate the flow of reserve water into said suction opening by increasing the impedance of said passage; said shutter having differently shaped body portions for deflecting 15 the flow of reserve water from said passage in different manners in accordance with the ratio of air to water in the main suction flow.

5. A pumping system for continuous pumping of air and water in varying mixtures without loss of prime which comprises a centrifugal pump having discharge and suction openings, a tank for reserve water directly connected to said discharge opening, a main suction connection for said suction opening, an aperture interconnecting directly said tank and said connection at a point close to the suction opening and forming a valve seat, a shutter member for control of reserve water through said aperture including a surface for seating onto said valve seat 30 against the force of flow of reserve water and including another surface for varying engagement with the main flow in accordance with the ratio of air to water thereof to counteract the force of flow of reserve water, and means for guiding 35 said shutter member with respect to said valve seat, said aperture having an opening area adjusted to balance the counteracting forces of the reserve and main flows upon said shutter member to provide approximate optimum conditions of high vacuum at high capacity operation and of short drinking time at low capacity operation for a given effective suction lift for the pump.

6. A pumping system for operation on varying mixtures of air and water comprising a centrifugal pump having a suction opening, a reservoir for priming water adapted to be refilled from the discharge of said pump, a suction connection for said opening for the main flow of air and water, an aperture interconnecting said reservoir and suction connection and forming a valve seat, and a hinged shutter member for seating onto said valve seat for control of the flow of reserve water, said shutter member having 55 a vane contacting at varying angles with the main flow in accordance with the ratio of air to water thereof and having different deflecting portions of differing configurations contacting with the flow of reserve water at the various angles of said vane to vary the deflection of the reserve flow by said shutter member in accordance with the ratio of air to water in the main flow and thereby varying the relation between the interacting forces upon said shutter member by the reserve and main flows for a substantially instantaneous adjustment of said shutter member in accordance with the ratio of air to water at any instant in said suction connection.

7. A pumping system comprising a centrifugal pump, a suction connection for the main water flow, a recirculation path for said pump including a reservoir, control means for recirculation water from said reservoir, said control means comprising a restricted outlet from said path opening directly into said suction connection 75 opening directly into said suction connection

above the level of the center of said pump and an automatic shutter for said outlet placed within said suction connection, said automatic shutter comprising a ball-shaped body portion arranged for control of said outlet and to be directly operated upon by the main flow in said suction connection. 5

8. A pumping system for continuous pumping of air and water, separately and mixed, without loss of prime which comprises a centrifugal 10 pump having a suction opening and a discharge opening, a main suction connection for said suction opening, a tank for reserve water connected to said discharge opening, a path from said tank joining said suction connection immediately in 15 front of said suction opening, a valve chamber at the point of juncture of said path and connection having a valve seat for each of said path and connection, respectively, a shutter within said chamber adapted to ply between and seat 20 onto said two seats, said shutter being under control of the forces of the opposing streams acting thereupon from said path and connection to control the proportion of reserve water to water in the main flow, and said shutter having 25 substantially spherical seating areas adapted to serve also as diffusing surfaces for spraying of the two streams into the segregated air in said chamber, and means within said chamber for guiding said shutter past said suction opening. 30

9. A self-priming pumping system for pumping air and water in varying proportions comprising a centrifugal pump having suction and discharge openings, a water reservoir directly interconnecting said openings for quick supplying of reserve water in response to reduction of the main water flow, valving means for automatically varying the passage of water between said reservoir and said suction opening under the varying force of the main water flow into 40 said suction opening, said valving means comprising an annular valve seat and an annular shutter member therefor, said member having a central opening for the passage of the main water flow into said suction opening. 45

10. A pumping system for pumping air and water in varying proportions comprising a centrifugal pump having a suction opening, a main suction flow connection and a reserve water connection for said suction opening, automatic valving means having an annular valve seat and a shutter member therefor to control the flow from said reserve water connection to said suction opening, said shutter member having a central opening for continuous passage of the flow from 55 said suction connection and having a surface subject to impact with the flow from said suction connection for movement of said member relative to said seat in accordance with the ratio of water to air in said suction flow. 60

11. A pumping system comprising a centrifugal pump, a suction connection for the main water flow, a recirculation path for said pump including a reservoir, control means for recirculation water from said reservoir, said control means comprising a restricted outlet from said path opening directly into said suction connection above the level of the center of said pump and an automatic shutter for said outlet placed within said suction connection, said automatic shutter comprising a flexible collar adapted to pass the main flow through its central opening. 65

12. A pumping system comprising a centrifugal pump, a suction connection for the main water flow, a recirculation path for said pump 70

including a reservoir, control means for recirculation water from said reservoir, said control means comprising a restricted outlet from said path opening directly into said suction connection above the level of the center of said pump and an automatic shutter for said outlet placed within said suction connection, said automatic shutter comprising a flexible collar having a substantially tubular expandable portion 10 and said outlet comprising a substantially annular opening in said suction connection.

13. A pumping system for continuous pumping of air and water in any proportion comprising a centrifugal pump, a suction connection, 15 a discharge connection, a water reservoir having curved contour and placed above said pump and directly interconnecting said connections, a strainer arranged within said reservoir to provide an even and practically unimpeded passage 20 of air and water in the main discharge flow substantially vertically upwards from said pump into said discharge connection and to provide a subdivided flow of water substantially free of debris and air into said reservoir, said strainer being 25 placed near the periphery of said reservoir and slightly inclined from the vertical direction of

the discharge flow from said pump to produce by said subdivided flow a centrifugal action within said reservoir for segregation of air to escape through said discharge connection, and an automatic valve at the bottom of said reservoir for 5 varying ejection of reserve water substantially freed of air directly into said suction connection, in accordance with varying proportions of air in the main flow through said suction connection.

14. A pumping system comprising a centrifugal 10 pump, a suction connection for the main water flow, a recirculation path for said pump including a reservoir, control means for recirculation water from said reservoir, said control means comprising a restricted outlet from said path 15 opening directly into said suction connection above the level of the center of said pump and an automatic shutter for said outlet placed within said suction connection, and further comprising a discharge connection for said pump, a diaphragm responsive to head pressures in said discharge connection, and mechanical means for interconnecting said diaphragm and said automatic shutter for at least partial compensation for the effective head pressure on said shutter. 20 25
